SHOE CONSTRUCTION

Seymour Troy, New York, N. Y.

Application April 4, 1932, Serial No. 602,973

2 Claims. (Cl. 36—45)

This invention relates to improvements in shoe construction, and particularly to the construction of the quarter and heel portion thereof.

The invention has for its object an improved construction for shoes and particularly for shoes of the turned variety, which is strong, durable, efficient and readily manufactured.

More particularly, an object of the invention is to provide an improved construction for the heel and quarter portion in women's shoes, whereby the heel is firmly held in contact with the quarter of the shoe, and whereby the danger of the heel separating from the quarter under severe strain, is substantially eliminated.

15 A further object of the invention is to provide a shoe construction, in which the normal outer covering of the quarter of a shoe is continued down about the heel, so as to fit snugly about the heel to cooperate with an extension of the 20 shoe sole forming the breast of the heel to hold the heel firmly against movement with respect to the quarter of the shoe.

Other objects of the invention will in part be obvious and will in part appear hereinafter.

25 The invention accordingly comprises the features of construction, combinations of elements and arrangement of parts, which will be exemplified in the construction hereinafter set forth and the scope of the application of which will be 30 indicated in the claims.

For a further understanding of the nature and objects of the invention, reference should be had to the following detailed description taken in connection with the accompanying drawing, in which:

35 Figure 1 is a perspective view with parts broken away, showing the construction of a lady's shoe of the turned variety embodying the present invention; and

40 Fig. 2 is a rear view of the shoe.

Referring now to the drawing, and particularly to Fig. 1, 10 denotes generally a shoe having a sole 11, a vamp portion 12, a quarter portion 13 and a heel 14. In the embodiment of the invention shown, the vamp portion is stitched to the sole in the usual manner. The quarter comprises a counter 15 preferably of relatively heavy material shaped to conform to the heel of the wearer and which gives the shape to the quarter portion of the shoe. On the outside of this counter are provided a fabric lining 16 and an outer covering 17, preferably of leather. Inside the quarter is provided a lining 18. The outer covering and the lining may be extended to form 50 an ankle strap 19. The counter 15 is held in

place by having its lower edge turned in and positioned between the upper face of the heel 14 and an extension 20 of the sole 11. In the preferred embodiment of the invention, the sole 11 is split, where it makes contact with the heel, 60 into two portions, the extension 20 which overlies the top of the heel and a portion 21 which covers the breast of the heel and extends down to the tap 22.

In the event that a sole is provided without the extension 20, the counter 15 will normally be held in place between the shank piece 23 and the upper face of the heel 14. The fabric lining 16, between the outer covering 17 and the counter, preferably terminates at or about the line 65 of contact between the upper face of the heel 14 and the extension 20 of the shoe sole. The inner lining 18 is preferably carried with the counter, so that its lower edge is held in place between the extension of the sole or the shank 70 piece and the upper face of the heel. The outer covering or upper 17 is carried smoothly down about the heel of the shoe, and may completely cover all portions of the heel, except the breast 75 and lower tap. The lower edges of the upper 17 are preferably inserted between the bottom of the heel 14 and the tap 22 and there held in place by suitable fastening means (not shown), for example, tacks or cement. The front edges of the upper are tightly drawn against the breast 80 of the heel and are preferably held in position between the heel and the extension 21 of the sole in any suitable manner, for example, by cementing or stitching with wire. To aid in positioning the extension of the upper about the heel and 85 to impart added strength to the structure, substantially the entire inner face of the extension of the upper is preferably cemented to the heel. 90

In the construction of the shoe, the material 95 which is to form the outer covering or upper for the quarter and heel portion of the shoe and which is preferably a high grade leather of comparatively great tensile strength, is first crimped or shaped to conform to the ultimate outline 100 of the quarter and heel. This may be done by hand or by pressing suitably treated material between suitably shaped dies. The parts of the shoe are then assembled on a last in the usual manner of manufacturing turned shoes. The 105 last is removed, the unfinished shoe is turned, the heel is affixed to the sole and the depending portion of the upper 17 is then drawn about the heel, cemented or otherwise fastened in place and the tap and breast-covering members suit- 110

ably positioned and fastened in place. A finished quarter and heel portion are shown in Fig. 2.

Not only does the structure described impart a novel and beautiful appearance to the heel portion of the shoe by eliminating the break or line between the heel and the quarter and by eliminating all seams in the quarter, but the structure imparts great additional strength to the heel of the shoe. It has been found that heels, and particularly the high heels of women's shoes, tend to pull away from the quarter and sole when any extra strain or shearing stress is placed upon the heel. This is particularly true where wooden heels are used. Some increased protection has been heretofore given by extending a portion at least of the sole along the breast of the heel, as shown for example in Fig. 1 at 21. However, the leather normally used in sole construction does not have a particularly high tensile strength. It is intended to resist wear, but it is not designed to resist tearing or shearing. Furthermore, the position of the strip of the sole along the breast of the heel is such that it does not offer resistance to the most frequent type of strain. Heels normally break away from shoe quarters, because an undue strain has been placed against the rear edge of the tap of the heel, tending to force the bottom of the heel forward and to pull away the rear portion of the heel from the sole. The extension of the sole along the breast of the heel offers substantially no resistance to this type of strain. On the other hand, the invention described above embodies a structure peculiarly designed to resist just this type of common strain. The leather normally used in the manufacture of shoe uppers is intended primarily to resist cutting, tearing, stretching, etc. It has, for its thickness, a relatively high tensile strength. In the construction shown in the drawing, the entire rear portion of the heel is encased and closely affixed to this strong tear-resisting covering.

It has been found that in shoes embodying the structure of the invention, it is practically impossible to tear the heel from the sole, save by the exertion of a stress which is seldom, if ever, met with in the actual use of the shoe. When a breast covering element is used of the type shown in Fig. 1, i. e. an extension of the sole, the heel is protected from strains in every direction, for the heel-encasing upper protects it adequately from strains from the rear and sides. It has been found that with shoe constructions of the

type described, wooden heels may be safely used without subjecting the wearer of the shoe to the danger of losing the heel.

While the embodiment of the invention de-

scribed above and shown in the drawing relates to women's shoes of the turned variety, it is to be understood that the invention is not to be so limited but is applicable to shoes made by any known process.

While the embodiment of the invention shown in the drawing illustrates a shoe in which the breast of the heel is covered by an extension of the sole, it is to be understood that the invention is intended to cover a shoe structure in which there is no direct connection between the breast-covering element and the sole.

Since certain changes may be made in the above construction, and different embodiments of the invention could be made without departing from the scope thereof, it is intended that all matter contained in the above description or shown in the accompanying drawing, shall be interpreted as illustrative and not in a limiting sense.

It is also to be understood that the following claims are intended to cover all of the generic and specific features of the invention herein described, and all statements of the scope of the invention which as a matter of language, might be said to fall therebetween.

Having described my invention, what I claim as new and desire to secure by Letters Patent is:

1. In shoe constructions of the character described, in combination, a quarter comprising a counter, a sole, a heel and an upper, the sole comprising two integral portions, one positioned to overlie a portion of said counter and the heel and the other forming the breast of the heel, and the upper consisting of a single piece of material adapted to substantially cover all of said quarter and all of said heel and intimately connected thereto.

2. A woman's shoe having in combination a counter, a leather upper, a heel and sole, said sole having integral sections, one adapted to overlie the breast of the heel, the other adapted to overlie a portion of said counter and said heel, the upper covering all of said counter and all of said heel, save that portion thereof covered by said sole, and cooperating with said sole to completely encase said heel and to protect it from strain in every direction.
